UNITED STATES PATENT OFFICE.

ALFRED B. FOWLER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,288,553.

Specification of Letters Patent. Patented Dec. 24, 1918.

Application filed May 19, 1915. Serial No. 29,029.

To all whom it may concern:

Be it known that I, ALFRED B. FOWLER, a citizen of the United States, residing at Beverly, in the county of Essex and State of Massachusetts, have invented certain Improvements in Lasting-Machines, of which the following description, in connection with the accompanying drawings, is a specification, like reference characters on the drawings indicating like parts in the several figures.

This invention relates to machines for lasting and securing together the upper and soles of boots and shoes and is herein shown and described as embodied in a machine for lasting and sewing stitch-down shoes. This invention is an improvement upon the machine for this purpose shown and described in British patent specification No. 4058/1912. The machine of the British patent is well adapted in most respects for the purpose of lasting and sewing stitch-down shoes. The gripper mechanism therein employed, however, requires for its most satisfactory operation a longer portion of the cycle of the machine than is available for it when the proper time is allowed for the operation of the sewing instrumentalities. The general object of this invention is to provide a gripper mechanism better adapted to the conditions existing in a lasting and sewing machine.

An important feature of the invention consists in the combination with upper fastening mechanism of means for applying a strain or tension to the margin of an upper, and means organized to hold a portion of said upper which is against the last from responding to the tensioning pull and then to release the upper momentarily and thereafter hold it again, whereby the pull is effected during a relatively short interval of the machine's cycle and without interference with the fastening inserting mechanism. In the construction shown, a work rest or support and a presser foot are provided by relative movement of which the outwardly extending margins of the upper and of the sole of a stitch-down shoe are clamped together, and a gripper is provided which seizes the margin of the upper extending beyond the work rest and applies through suitable yield-

ing mechanism a strong pull to the said extending margin. The pull, however, does not at first affect the portion of the upper extending about the last because an intermediate portion of the upper is clamped to the sole by the work rest and the presser foot. At the proper time in the cycle of the machine, the presser foot is momentarily released, and the gripper is then operated by the reaction of the yielding element in the pulling mechanism to effect a strong tensioning pull upon the upper to draw it about the last. The upper and sole margin are then again clamped by the work rest and presser foot and are penetrated by the awl. The upper being now held from retraction by the awl, the gripper is released and the pressure of the presser foot relaxed to permit feed movement of the work by the awl. Since the gripper has released the upper, it is unnecessary for it to participate in the feed movement of the awl.

Another feature of the invention consists in a movable gripper comprising relatively movable jaws, a device for resisting movement of the gripper, and operating mechanism connected to the gripper jaws and acting first to close the jaws and then acting in opposition to the resisting device to move the gripper. In the construction shown, the gripper is pivoted for movement about a center located below the gripping faces of its jaws and a friction device is located on the axis about which the gripper swings. The gripper jaws are, as shown, connected by a toggle mechanism through movement of which by the operating mechanism the jaws are closed, the operating mechanism then acting to swing the gripper about its pivot. This construction, comprising the friction means, also insures that the gripper jaws will be opened before the gripper is again moved toward the shoe to seize another portion of the upper.

Another feature of the invention consists in means for deflecting the upwardly projecting margin of the upper outwardly into position to be seized by the gripper. The deflector is preferably resiliently mounted so that it may be moved rearwardly by pressure of the upper as the upper is placed in the machine and does not interfere with its

introduction, and it is also resiliently depressed against the work, means being provided for manually raising the deflector initially to permit it to come into engagement 5 with the upper face of the outturned margin of the upper.

These and other features of the invention including certain combinations of parts and more important details of construction will 10 appear in connection with the following description of the preferred form of the invention when read in connection with the accompanying drawings, and will be pointed out in the claims.

15 In the drawings,

Figure 1 is a side view of a machine embodying the invention;

Fig. 2 is a detail of the mechanism for operating the awl;

20 Fig. 3 is a front view of the gripper mechanism and adjacent portions of the machine;

Fig. 4 is a detail, partly in section, of a portion of the gripper operating mech- 25 anism;

Fig. 5 is a detail view of the mechanism for operating the presser foot;

Fig. 6 is a detail view showing the stock deflector and adjacent operating parts of 30 the machine; and

Figs. 7 to 11 show diagrammatically successive steps in the operation of the gripper, the presser foot and the awl upon the work.

Referring to Fig. 1 of the drawings, the 35 reference character 2 indicates the frame of the machine head in which is journaled the main cam shaft 4. The shaft 4 is driven by power applied to the combined hand and pulley wheel 6 and carries the various cams 40 from which the movements of the machine parts are derived. It will be unnecessary for the purposes of description of the present invention to enter into a complete description of the sewing instrumentalities 45 which are substantially similar to those of the commercial outsole stitcher shown, for example, in United States Letters Patent No. 473,870, granted April 26, 1892 on application of French & Meyer.

50 The sewing mechanism comprises a curved awl 10 and a curved hooked needle 11, Fig. 3. The awl, after it penetrates the work, is given a movement toward the operator's left and laterally of the machine to feed the 55 work which rests on a work support or table 12, the table having an elongated opening to permit such feed movement of the awl.

The awl operating mechanism is shown in Fig. 2. The awl carrier 15 is mounted for 60 rotation about an axis 16 and has a toothed segment which meshes with a corresponding segment on the lever 17 which has a fulcrum at 18 about which it is operated by a path cam on the cam block 19, as shown. 65 The lateral feed movement of the awl car-

rier is effected, as usual, by movement of a slide 21, Fig. 1, which is connected to a lever 22 pivoted at 23 and has a rearwardly extending arm 24 carrying a cam roll which engages a cam on the main shaft. A presser 70 foot 14 is provided which cooperates with the work support to hold the work during the work penetrating movement of the awl and during the formation of a stitch by the needle and the other sewing mechanism. 75

The presser foot operating mechanism, as shown in Fig. 5, comprises a presser foot 14 which contacts with the marginal portion of the tread face of the sole and is forced into clamping engagement to hold the work 80 against the work support 12 at the proper times in the cycle of the machine by means of a cam 20 on the main shaft 4. The presser foot 14 is mounted on a lever 25 pivoted at 26 having teeth 27 on its rear 85 face which are engaged by a locking pawl 28 mounted on a stationary pivot. Another lever 29 is mounted on the pivot 26 and is connected with the lever 25 through a spring 31. The lever 29 has ratchet teeth on its rear 90 end which are engaged by a pawl 33 carried by a lever 35 fulcrumed at 37 and operated by a cam roll engaging the cam path 39 in the block 20. It will be observed that the cam path 39 has two portions P and F which 95 act upon the lever 35 to depress its forward end and that the said lever carries a projection 41 which is adapted to engage a corresponding projection on the pawl 28 when the lever 35 is depressed and disengage it from 100 the teeth 27, thereby unlocking the presser foot and permitting the work to be fed or the upper to be tensioned between the presser foot and the work rest. At such times also the presser foot may be raised 105 if desired by the handle 43. At other times in the cycle the presser foot is held locked by the pawl 28 in whatever position it is forced by the pawl 33 acting upon the lever 29 and upon the presser foot 14 through 110 the spring 31. The timing of the cam 20 will be fully explained hereinafter.

The gripper mechanism by which the upper is tensioned and worked into position for the operation of the sewing mechanism 115 comprises a lower jaw carrier 30 pivoted at 32 to a bracket 34 secured at 36, Fig. 3, to the front of the machine. The jaw carrier is forked at its lower end to embrace a lug 38 on the bracket 34, through which fork 120 and lug the pivot rod 32 extends. To the upper end of the carrier 30 is adjustably secured by the screw 40 the lower jaw 42 of the gripper which extends laterally to the left and forwardly into a position directly 125 behind the work support 12 and with its gripping face substantially in the plane of the upper face of the work support. An upper jaw carrying slide 50 is mounted for vertical movement in the upper end of the 130

carrier 30, and secured to the slide 50 by a screw 52 is an upper jaw 54 which extends laterally to the left and forwardly into a position to bring its work engaging portion 5 over that of the lower jaw 42.

Mechanism is provided for closing the gripper jaws upon the work and swinging the gripper about the axis 32 to tension the upper outwardly of the shoe and substantially in the plane of the last bottom. The upper jaw carrier 50 is connected to the lower jaw carrier 30 by a toggle comprising links 56 and 58 pivoted together at 60 and to the upper jaw carrier 50 at 62. The lower end of the toggle is pivoted on the axis 32. Stop projections at 64 are provided on the rear sides of the toggle members to prevent the toggle from being bent outwardly beyond a straightened position, 15 and a screw 66 is provided to limit the movement of the jaws toward the work and to provide means for varying the position of the jaws relatively to the work when they close. It will be apparent that bending of 20 the toggle inwardly of the machine will cause the upper jaw to approach the lower jaw and also that the force applied to bend the toggle will, if the toggle cannot bend, swing the lower jaw carrier 30 about the 25 axis 32. Bending force is applied to the toggle through a link 68 pivoted to a projection on the lower toggle link at 70 and having the other end resiliently connected to an operating lever 72, Fig. 1. The lever 72 30 is pivoted between its ends to the machine frame at 74 and carries at its upper end a cam roll 76 which engages a cam path 78 in a cam block on the main shaft of the machine. The lower end of the lever 72 is pivoted to a sleeve 80, Fig. 4, mounted to slide 35 on a rounded stem of the link 68. The stem has a shoulder 82 between parts of different diameter, the sleeve being fitted to slide on the portion of larger diameter. A washer 40 84 is fitted to the portion of the stem having the smaller diameter and normally rests against the shoulder 82, being held in that position by a compression spring 86, which at its other end abuts against a flange 88 45 on a sleeve 90 held on the stem by nuts 92. The shoulder 82 limits the movement of the washer 84 and permits the spring 86 to be placed under any desired degree of initial or normal tension by means of the nuts 92. 50 Another compression spring 94 is held between a shoulder at the outer end of the larger rounded portion of the stem and the sleeve 80. The springs 86 and 94 are therefore opposed to each other, but the spring 55 86 is stiffer than the spring 94 so that the washer 84 is held normally against the shoulder 82. The sleeve 90 prevents excessive movement of the washer 84 and sleeve 80 by compression of the spring 86 which 60 might otherwise carry the sleeve 80 off of

the larger portion of the stem on to the smaller portion and permit the sleeve to catch on the shoulder 82.

To insure that the toggle will be broken to cause the gripper to close upon the stock 70 before the gripper is swung about the axis 32 to tension the upper outwardly, it is necessary to provide means to resist movement of the member 30 about the axis 32. In the construction shown a friction washer 75 100 of felt, fiber or other suitable material is provided on the rod 32 which engages the member 30 and against which it is pressed by a spring 102 the tension of which is controlled by a nut and washer at 104. A friction plate 106 is placed between the spring 102 and the washer 100 and is held from rotation by a stud 108 engaging the frame of the machine.

The shoe is presented to the machine with 85 the bottom up and with the sole substantially in a horizontal position, and the upper, which is loosely assembled on the last, has a tendency to project upwardly around the edge of the sole in a position nearly 90 at right angles thereto. It is consequently desirable to provide means for deflecting the margin of the upper material outwardly of the shoe in a position parallel to the last bottom so that it may be readily 95 seized by the gripper. In the construction shown, this function is effected by a stock deflecting mechanism comprising a finger 110, Fig. 6, having an end bent inwardly of the machine which serves as a foot to engage the inner face of the upper and bend it into a position substantially in the plane of the gripping faces of the gripper jaws. The deflector is held resiliently depressed 100 against the work by a spring 112 mounted 105 upon a pivot 114 about which the deflector is movable. The deflector 110 is provided with an extension 116 beyond its pivot which serves as a finger piece for lifting the deflector when the work is inserted in 110 the machine to insure that it will be positioned upon the upper face of the projecting margin of the upper. The pivot 114 of the deflector is on the lower end of a stem 120 which extends vertically through 115 an ear 122 of the machine frame and permits movement of the deflector about a vertical axis. A torsion spring 128 one end of which is secured by a screw 130 and the other end of which engages the stem 120, 120 Fig. 6, holds the deflector resiliently toward the shoe but permits it to be pushed back by the work in case the work is inserted before the deflector is lifted by the finger piece 116.

The operation of the machine is as follows:

The last with an upper and a sole assembled thereon is presented to the machine with the margin of the sole and the margin 130

of the upper extending between the work support 12 and the presser foot 14 which is normally unlocked when the machine is at rest and is manually raised for this 5 operation by the handle 43. The deflector 110 is positioned on the face of the upwardly extending upper by manipulation of the finger piece 116. The machine is now started. The presser foot is first actuated 10 to firmly clamp a portion of the margin of the sole and the projecting margin of the upper against the sole rest 12 and the lever 72 is actuated to break the toggle 56, 58. Owing to the friction produced by the 15 washer 100 and spring 102 resistance is offered to swinging movement of the carrier 30, and the first effect of breaking the toggle is to lower the jaw 54 into gripping relation to the jaw 42 to securely grip the 20 stock, Fig. 7. Further action of the lever 72 through the collar 80 tends through compression of the spring 86 to swing the carrier 30, but this movement is prevented by resistance of the stock which is still firmly 25 clamped by the presser foot against the work support. When the spring 86 has been fully compressed the pressure of the pressed foot is momentarily relieved by the action of the part P of the cam path 39 on 30 the cam roll carried by the lever 35 and the spring 86 reacts to swing the carrier 30 and the gripper to tension a part of the stock, Fig. 8, which is in advance of the part just fastened. After the stock tensioning 35 operation the presser foot 14 again clamps the sole and upper against the work support, Fig. 9, for the passage of the awl 10 through the tensioned upper and the margin of the sole, Fig. 10. After the passage of 40 the awl through the work the gripper is opened and the presser foot is released by the part F of the cam path 39, the stock being prevented from drawing back by the awl 10. The awl then moves laterally to 45 feed the work while the gripper first opens and then moves forwardly to engage a new portion of the stock presented to it by the work feeding movement of the awl, Fig. 11. The presser foot again clamps the work during 50 the stitch forming operation of the sewing mechanism, the gripper again closes upon the new portion of stock, Fig. 7, the spring 86 is compressed and acts again to tension the new portion of stock as soon as 55 the pressure of the presser foot is relieved. This cycle of operations is repeated along the periphery of the shoe bottom.

Having fully described my invention, what I claim as new and desire to secure by 60 Letters Patent of the United States is:

1. In a machine of the class described, the combination of upper fastening mechanism, means for applying a tensioning strain to a portion of the margin of an upper, means 65 organized to hold a portion of the upper

which is adjacent to the last from responding to the tensioning pull upon the margin, and means for momentarily releasing the holding means and thereafter causing it again to hold the upper whereby the tensioning of the upper is effected in a relatively short portion of the machine's cycle and without interference with the fastening mechanism. 70

2. In a lasting machine for stitch-down 75 shoes, the combination of a rest to receive the outturned margin of the upper, a presser foot, means for operating the presser foot to clamp the work against the rest, a gripper, means including a spring for operating 80 the gripper to seize the upper and place the spring under tension while the upper is held clamped against the rest, means for releasing the presser foot to permit tensioning of the upper by the reaction of the spring, and 85 means for fastening the upper.

3. In a machine of the class described, the combination with means for sewing the upper and sole together, of means for holding the margin of the upper and the outsole 90 clamped together during the sewing operation, a gripper, resilient means through which the gripper is operated, means for placing the resilient means under tension during the sewing operation, means for releasing the clamping means to permit the gripper to act to tension the upper, means for again operating the clamping means to hold the margin of the upper and the sole 95 together for the penetrating movement of 100 the awl, and means for releasing the gripper during the feed movement of the awl.

4. In a stitch-down lasting machine, the combination of fastening inserting mechanism, work clamping means, work tensioning means including a resilient element, and means for effecting the clamping of the work while a fastening is inserted in one portion of the clamped work and while energy is stored in the resilient means and then releasing the clamping means to permit an adjacent portion of the upper to be tensioned about the last by the reaction of the resilient element of the tensioning means. 105 110

5. In a machine of the class described, the 115 combination of work clamping means, work feeding means, fastening inserting means, work tensioning means including means for storing energy while the work is clamped and while a fastening is being inserted in 120 one part of the portion of the work which is clamped, and means for then releasing the work to permit application of the stored energy to the other part of the previously clamped portion to tension it. 125

6. In a machine of the class described, the combination of sewing means, an awl for penetrating and feeding the work, a gripper for seizing and tensioning the work, and a resilient element in which energy is stored 130

during one portion of the cycle of the machine and is released during a later portion of the cycle for rendering the tensioning means effective in the interval between the 5 completion of the formation of a stitch by the sewing means and the feeding movement of the work by the awl for the next stitch.

7. In a machine of the class described, the combination of sewing means, awl feeding 10 means, a work support, a presser foot, means for operating the presser foot to hold the work clamped upon the support during the stitch forming operation, a gripper, gripper operating mechanism including resilient 15 means for applying a tensioning strain to the margin of the upper outside the portion held by the presser foot and in advance of the portion being sewed, means to release the presser foot to permit the tensioning 20 strain to act on the portion of upper beyond the presser foot to tension the upper about the last before the work is fed, means for operating the awl to penetrate the work before the gripper releases it, means for 25 releasing the gripper, and means for raising the presser foot to permit feed movement of the work by the awl.

8. In a machine of the class described, the combination of work supporting means, 30 a gripper comprising upper and lower jaws having gripping faces arranged in a horizontal plane and mounted for swinging movement about a center a substantial distance from the plane of the shoe bottom at 35 the side of the bottom on which the upper is disposed, a toggle for closing the gripper jaws, and means for operating the toggle first to close the gripper jaws and then to swing the gripper upon its mounting outwardly of the shoe to tension the upper.

9. In a machine for lasting stitch-down shoes, the combination of a work rest to receive the outturned flange of an upper, a 40 movable gripper having gripper jaws arranged to grip the margin of the flange in the plane of the upper face of the work rest, a toggle pivoted at its ends to the respective jaws, and operating connections acting on the toggle between its ends to break the 45 toggle to close the jaws and then acting to move the jaws substantially in the plane of the projecting margin of the shoe to apply tension to the upper.

10. In a machine for lasting stitch-down 50 shoes, the combination of a work rest to receive the outturned flange of an upper, a gripper having gripper jaws arranged to grip the margin of the flange in the plane of the upper face of the work rest, and 55 mechanism including a single resilient means acting first to close the jaws resiliently upon the upper and then to apply a resilient pull upon the upper outwardly of the shoe.

11. In a machine of the class described, 60 the combination of a movable gripper com-

prising relatively movable jaws, a friction device resisting movement of the gripper, and operating mechanism connected to one jaw of the gripper acting to close the jaws and then acting in opposition to the friction device to move the gripper to tension the upper, the friction device insuring that the gripper is open prior to its return movement.

12. In a machine of the class described, 70 the combination of a gripper pivoted for movement as a whole about a center, said gripper comprising a movable jaw and a relatively fixed jaw, and operating connections to the movable jaw acting first to close 75 the jaws and then to move the gripper about its pivot, the said connections acting to open the jaws before the return movement of the gripper about its pivot.

13. A machine of the class described having, in combination, a gripper pivoted for movement about an axis and comprising relatively movable jaws, and operating connections for closing and opening the jaws and moving the gripper about its axis, the 80 gripper being constructed and arranged to offer resistance to movement about its axis in either direction which is greater than the resistance to opening or closing of the jaws so that the operating connections will close 85 the jaws before they move the gripper about its axis in one direction to tension the upper and will open the jaws to release the upper before they move the gripper about its axis in the other direction to normal 90 position.

14. In a machine of the class described, the combination of upper gripping means comprising relatively movable jaws, and operating connections for causing the jaws 100 to close upon the work and then for moving the jaws to tension the work, said connections including a friction element for insuring that the closing movement shall precede the tensioning movement and also insuring that the opening movement of the jaws shall precede the return movement of the jaws after their tensioning movement.

15. In a machine of the class described, 110 the combination of upper seizing and tensioning means comprising relatively movable jaws forming a gripper which is movable to tension the upper, operating connections for causing the jaws to close and which thereafter move the grippers to tension the upper, and friction means opposing movement of the gripper in either direction and insuring that the jaws shall open prior to the return movement of the gripper after the tensioning movement.

16. In a machine of the class described, 120 a gripper, a toggle connecting the upper jaw and the lower jaw, the lower joint of the toggle forming a pivot about which the gripper is moved to tension the upper, and fric- 130

tion producing means at the lower end of the toggle to insure that the toggle will be broken to close the gripper jaws before the gripper is moved about its pivot to tension the upper.

17. A machine of the class described having, in combination, a work rest, a lower jaw carrier mounted to swing about a pivot below the work engaging face of the rest, 10 an upper jaw, an upper jaw carrier mounted for movement in the lower jaw carrier, a toggle connecting the upper jaw carrier to the lower jaw carrier, and means for breaking the toggle to close the jaws and 15 swing the carrier.
18. In a machine of the class described, a gripper comprising a lower jaw pivoted for swinging movement toward and from the work, an upper jaw having a depending 20 stem mounted to slide in the lower jaw, and means acting first to move the upper jaw relatively to the lower jaw to seize the work, and thereafter acting to swing both jaws to tension the work.
19. In a machine of the class described, a movable gripper, a toggle for closing the gripper jaws, operating means for the toggle acting between its end joints for breaking the toggle to close the jaws, and a stop 30 preventing movement of the toggle beyond a straightened position and through which force is applied to move the gripper about the lower pivot of the toggle toward the work.
20. In a machine of the class described, the combination of a gripper, operating means for moving the gripper toward and from the work, and a connection between the gripper and the operating means which 40 is resilient in both of said directions of movement.
21. In a machine of the class described, the combination of a gripper, and operating means for moving the gripper toward

and from the work which is weakly resilient 45 in one direction of said movement and strongly resilient in the opposite direction.

22. In a machine of the class described, the combination of a gripper for seizing and tensioning an upper, and operating means 50 for the gripper which operates the gripper through a strong spring to tension the upper and moves the gripper toward the upper through a weak spring.

23. In a machine for lasting and sewing 55 stitch-down shoes, the combination of a gripper constructed to seize and tension outwardly the outturned margin of the upper, and a deflector constructed and arranged to engage the inner face of the upper and deflect outwardly and downwardly the said margin into substantially the plane of the gripper jaws in position to be seized by the gripper.

24. In a machine for lasting and sewing 65 stitch-down shoes, the combination of a gripper acting substantially in the plane of the last bottom to seize and tension the upper outwardly of the shoe, a finger for engaging the stock and deflecting it outwardly 70 of the shoe into position to be seized by the grippers, and resilient means for pressing the finger downwardly against the stock.

25. In a machine for lasting and sewing 75 stitch-down shoes, the combination of a gripper acting substantially in the plane of the last bottom to seize and tension the upper outwardly of the shoe, a finger for engaging the stock and deflecting it outwardly 80 of the shoe into position to be seized by the grippers, and resilient means for holding the finger toward the shoe and permitting it to be moved by the pressure of the upper prior to its being raised above the upper into stock deflecting position.

95
In testimony whereof I have signed my name to this specification.

ALFRED B. FOWLER.

Copies of this patent may be obtained for five cents each, by addressing the "Commissioner of Patents, Washington, D. C."
